Hague Farley

Patented Jan. 3, 1928.

UNITED STATES PATENT OFFICE.

MARCEL M. MICHELIN, OF STATEN ISLAND, NEW YORK, ASSIGNOR TO PINAUD INCORPORATED, OF NEW YORK, N. Y., A CORPORATION OF NEW YORK.

DESIGN FOR A JAR OR SIMILAR CONTAINER.

Application filed September 24, 1927. Serial No. 23,538. Term of patent 14 years.

To all whom it may concern:

Be it known that I, MARCEL M. MICHELIN, a citizen of the Republic of France, a resident of Staten Island, Richmond County, New York State, have invented a new, original, and ornamental Design for a Jar or Similar Container, of which the following is a specification, reference being had to the accompanying drawing, forming a part thereof.

Fig. 1 is a top view; and
Fig. 2 is a side view.

I claim:

The ornamental design for a jar or similar container substantially as shown.

MARCEL M. MICHELIN.
